UNITED STATES PATENT OFFICE.

VICTOR F. JONES, OF CHICAGO, ILLINOIS.

NECKTIE-HOLDER.

1,109,680.

Specification of Letters Patent.

Patented Sept. 8, 1914.

Application filed August 28, 1913. Serial No. 787,077.

To all whom it may concern:

Be it known that I, VICTOR F. JONES, a citizen of the United States, residing at the city of Chicago, in the county of Cook and State of Illinois, have invented certain new and useful Improvements in Necktie-Holders, of which the following is a specification.

This invention relates to improvements in a holder for neckties of the four-in-hand type, and it consists in certain peculiarities of the construction, novel arrangement and operation of the parts thereof, as will be hereinafter more fully set forth and specifically claimed.

The object of my invention is to provide a holder for neckties which shall be simple and inexpensive in construction, light in weight, compact in form, yet strong, durable and efficient in operation, or for the use for which it is intended, that is, to afford means for more easily or readily forming the tie or knot at a certain or proper point on the scarf, and in such a manner that a neat, attractive and smooth knot may be formed and held or maintained against displacement with respect to the shirt collar, as well as, against parts of the knot itself becoming loose and assuming an unattractive appearance.

In order to enable others skilled in the art to which this invention pertains to make and use the same, I will now proceed to describe it, referring to the accompanying drawing, in which—

Figure 1 is a front face view of the holder; Fig. 2 is a longitudinal sectional view taken on line 2—2 of Fig. 1; looking in the direction indicated by the arrows; Fig. 3 is a front view of the holder showing a portion of the scarf or necktie located therein in the initial step of forming the knot; Fig. 4 is a perspective view of a portion of the scarf or necktie with the holder in place and the parts arranged as they will appear in the second step of forming the knot; Fig. 5 is a fragmental face view of the scarf showing the holder thereon and illustrating the third step employed in forming the knot, and Fig. 6 is a similar view showing the completed knot and illustrating the holder by dotted lines.

Like numerals of reference refer to like parts throughout the different views of the drawing.

The holder is designated as a whole by the reference numeral 7, and consists of a

single piece, preferably of sheet metal, including an elongated body 8, having its rear surface or back flat and straight, as shown in Figs. 1 and 2 of the drawing, and provided on each of its sides with a forwardly and inwardly extended flange 9, the adjacent edges of which are approximated at their lower portions, but gradually separated or widened toward their upper portions. 60 These flanges are located at a slight distance in front of the face of the body 8, so as to permit of the insertion therebetween of a portion of the scarf or necktie 10, which may be of the ordinary four-in-hand style 65 or type.

The lower portion of the body 8 of the holder is downwardly tapered and provided at its lower end with a pointed projection 11, to pierce or engage the scarf 10, as will be readily understood by reference to Figs. 3 to 6 inclusive of the drawing. The upper portion of the body 8 of the holder is provided with a forwardly and downwardly extended tongue which, by preference, projects at its free end to and between the upper portions of the flange 9, yet slightly forwardly of the same, as will be readily understood by reference to Fig. 2 of the drawing. 85

In using the holder, the necktie or scarf 10 is formed with a loop 13 (see Fig. 4), which fits around the band of the collar, which is attached to the shirt in the ordinary manner at its rear central portion, and 90 at its front ends, and which collar may be of the ordinary or any preferred construction. One strand 10^a of the scarf or necktie 10 is placed between the tongue 12, flanges 9, and front surface of the body 8, of the holder in about the position shown in Fig. 3, and the holder 7 is secured in such position by means of the pointed projection 11, which pierces or engages the strand 10^a of the tie or scarf. The other strand 14, of the 95 loop 13, of the tie or scarf is then placed across the front of the holder 7, but rearwardly of the tongue 12, and in front of the flanges 9, as is clearly shown in Fig. 4 of the drawing, which figure illustrates the 100 second step in the formation of the knot of the necktie or scarf. When the parts are thus positioned, the tie or scarf 10 is drawn around the band of the collar to the proper tension, and so that the upper portion of the holder 7 will be located at the proper 105 point in front of the collar button, when by 110

passing the strand or portion 14 of the tie or scarf rearwardly of the holder 7, and then in front of the same so as to overlap the flanges 9, as well as the lower portion of the tongue 12, as shown in Fig. 5, the third step of forming the knot is completed. The fourth and last step of forming the knot consists in passing the strand or portion 14 of the tie rearwardly of the holder 7, and 10 upwardly at the back thereof, and then downwardly over and in front of the tongue 12, and flanges 9, yet rearwardly of the fold or loop 15 formed by the third step employed in forming the knot. After this 15 last step has been performed, the loop 15 can be slid upwardly and the knot tightened or made smaller by pulling the strand or portion 14 downwardly, in which position the parts of the tie will be firmly held 20 against displacement with respect to the shirt collar, as well as against the portion of the knot becoming loose so as to spoil the attractiveness of the knot.

From the foregoing and by reference to 25 the drawing, it will be readily understood and clearly seen that a necktie holder embodying my improvements is of an extremely simple and inexpensive construction and that it will not be discernible in its use, 30 but will serve to prevent the tie sagging downwardly so as to expose the collar button, which so often occurs and is quite objectionable, and at the same time will prevent the tie slipping in such a manner as 35 to disfigure the knot thereof. It is evident that the holder will offer little or no obstruction to untying the knot or removing

the tie from the collar, and besides, that by reason of the engagement of the flanges, tongue and pointed projection of the holder with the tie or scarf, after it is once applied thereto at the proper point for forming the knot, it will be in position for repeated use. 40

Having thus fully described my invention, what I claim as new and desire to secure by 45 Letters Patent, is—

1. As an improved article of manufacture, the herein described necktie holder consisting of an elongated body having at its upper part a forwardly and downwardly projected tongue and at each of its sides a forwardly and inwardly extended flange, the 50 said tongue and flanges being spaced from the front face of said body, separated from one another, and the upper ends of said flanges terminating below the lower end of the tongue.

2. As an improved article of manufacture, the herein described necktie holder consisting of an elongated body having at its 55 lower end a pointed projection and at its upper part a forwardly and downwardly projected tongue and at each of its sides a forwardly and inwardly extended flange, the 60 said tongue and flanges being spaced from the front face of said body, separated from one another, and the upper ends of said flanges terminating below the lower end of the tongue.

VICTOR F. JONES.
